9 Claims. (Cl. 323—74)

cations, difficulties and costs. For instance, a vacuum tube requires being heated, and its accuracy for use in analog computers depends on the straightness of the $I_p - E_g$ curve. Other devices hitherto proposed have a limited range of utility or are again too complicated for economical use.

Now, my invention provides a novel voltage-divider or potentiometer device, whose deviation from standard structure involves only resistances and switches, and which will give accurate voltage-division under load, regardless of the magnitude of such load or of variations in such magnitude during use.

For a better understanding of my invention, reference is now made to the accompanying drawings, in which:

15 Fig. 1 is an electrical diagram which aids in explaining the principle of my invention.

Fig. 2 is an electrical diagram showing a practical embodiment of the principles taught by Fig. 1, using a special form of resistor B which is shown in greater detail in

20 Fig. 3. Fig. 2 further illustrates the use of this embodiment in a cascaded system, in certain special applications of this invention.

25 Fig. 3 is a top view of a laminated resistor B which constitutes an integral part of this invention.

Basic theory

Referring now to Fig. 1 in detail, three types of lines are to be distinguished there. The heavy lines represent electrical resistances, fixed or variable. Lighter lines represent electrical connecting wires of negligible resistance, or whose resistance does not enter into the calculations. These lighter lines are permanently attached to the other resistances at certain points (indicated by heavy dots) or they may be "plugged into" the other resistances (indicated by heavy arrows). Discontinuous, light dimension lines (terminating in light arrows) indicate the extent of the various electrical quantities indicated, such as the extent of resistances A, B and R, or of potential differences E and e. A conventionally indicated cell or battery makes a closed circuit with the variable resistance

This invention relates to electrical devices of the potentiometer or voltage divider class. It is an object of this invention to provide novel devices of this type which can be used to measure off a specified fraction of a voltage or of a resistance, even while the device carries a load, without detriment to the accuracy of the measurement by virtue of said load or of variations therein. Additional objects and achievements will become apparent as the description proceeds.

The potentiometer or voltage divider is a well-known device in electrical measurements or instruments. The elementary form thereof, as well as its principle of operation is described in many textbooks or manuals. See, for instance, "Analog Methods in Computation and Simulation" by Walter W. Soroka (McGraw-Hill, 1954), page 48, or "Radio Communication Pamphlet" No. 40 (Government Printing Office, 1922), pages 55 to 57 and 84 to 86.

Devices of this type have numerous applications in the design of electrical instruments, in electrical measurements, in radio communication, etc. A particular and relatively recent field of application is in the building of calculating machines and servo-mechanisms. See, for instance, "Servomechanism Practice" by William R. Ahrendt (McGraw-Hill Book Co., 1954), chapter 2, or the Soroka book above referred to.

A serious limitation, however, on the use of potentiometers for the last mentioned purpose is their inherent property of giving an accurate voltage division only if the principal resistance of the device carries no side loads. If the device be used for measuring an unknown E. M. F., the latter must be shunted across certain points of the graduated potentiometer resistance, but the points selected must be such that no current whatever flows through the shunt. A galvanometer included in the shunt must read zero. If this condition is violated, the reading is no longer accurate.

Again, for many purposes, devices of the above type are of interest for dividing a given voltage or a given resistance in specified ratio, rather than for measuring an unknown voltage. For instance, a circuit may be given wherein the drop of potential across a certain, principal resistance is 100 volts, and it may be required to draw off from it an E. M. F. of 40 volts. If the principal resistance is uniform and graduated, it is easy to locate two points on it whose difference of potential is precisely 40 volts. But the instant that a "load" (another instrument, resistance, lamp, etc.) is attached to these two points, to make use of the 40 volts, the value of the latter changes (usually drops), and we are no longer certain what the voltage is under which the load is operating.

Attempts to overcome this difficulty have already been made in the art. Chapter 2 of the above cited textbook of Soroka describes several of these. They have, however, certain other drawbacks. The solution wherein vacuum tubes are interposed between the voltage divider and its load has the disadvantage of introducing vacuum tube elements into the circuit, with all their attendant compli-

system A—B. E is the terminal voltage of this cell or battery.

Restating now my invention in different words, the principal aim of the device is to enable us to lay off on line AB a voltage e which is less than E but whose ratio to E has been assigned to us. In other words, given a fractional number x , ($0 < x < 1$); the problem is to produce an electrical instrument on which we can readily lay off a voltage $e = xE$, wherein E is the terminal voltage of the system, the actual value of E itself being immaterial, and perhaps unknown.

It will be noted that in Fig. 1 we have a resistance system comprising a variable resistance A in series with a parallel system consisting of fixed resistance R and variable resistance B. Hereinafter we shall call the series A—B, the basic resistance line of the system; resistance R, the shunt or load; and the effective resistance of the entire system A—BR, the total resistance under E.

Two basic conditions will now be imposed upon the device of my invention.

(1) The total resistance under E must have the value R and must remain constant, no matter what the position of the shunt R is along the basic line A—B.

(2) When the shunt is replaced by a load, the resistance of the latter must likewise have the value R and must be kept constant no matter how conditions within the load circuit are modified.

It follows at once from condition 2, that shunt R may be replaced by another resistance system A—BR, which obeys condition 1. Then the shunt R in the latter, may be replaced by a third similar system. And so on. In this fashion a cascade of devices of this nature can be assembled, while yet maintaining the total resistance under E at the value R. This value R, we shall hereinafter designate as the basic resistance value or the basic unit.

Now, to develop the problem, let U = the total resistance of system A—BR, and let R_1 = the resistance of the parallel system BR.

Then

$$U = A + R_1; \frac{1}{R_1} = \frac{1}{B} + \frac{1}{R}, R_1 = \frac{BR}{B+R}$$

Hence

$$U = A + \frac{BR}{B+R}$$

Let e = drop of potential across the system BR; then

$$\frac{e}{E} = \frac{R_1}{U} = \frac{R_1}{A+R_1}$$

It follows that, given

$$x = \frac{e}{E}$$

all we need to do is to plug in shunt R along basic line A—B at such points that

$$\frac{R_1}{A+R_1} = x$$

Now, we have postulated that U must equal R at all times. So, replacing U by R in the above formulas, we obtain

$$x = \frac{R}{R_1} = \frac{B}{B+R}; R = A + \frac{BR}{B+R} = A + xR \\ \therefore A = R(1-x); B = x(B+R)$$

$$B = \frac{xR}{1-x}$$

and finally, $AB = xR^2$.

It will be noted that

as $x=0$, $A=R$, $B=0$ and $e=0$

as $x=1$, $A=0$, $B=\infty$ and $e=E$, and

when $x=0.5$, $A=0.5 R$, $B=R$ and $e=0.5 E$

When these figures are applied to the diagram of Fig. 1, it will be clear that as $x=0$, the two plugging-in arrows of shunt R come together on line A—B at the point thereon marked R. As $x=1$, the left-hand arrow recedes to the extreme left of the A—B line, whereas the arrow on the right, while still in contact with the corresponding arrow from the battery, runs off the diagram on the righthand side toward infinity.

Observing from Fig. 1, that the shunt R is plugged in on basic line A—B at points a and b , the practical problem on hand reduces to the following:

Given a positive fraction x and a basic resistance unit R, to devise a basic line of resistances A and B so that by a simple mechanical motion (translation or rotation) proportional to x , we may be able to locate on the basic line points a and b so that

$$A = R(1-x) \text{ and } B = \frac{xR}{1-x}$$

For a practical solution to this problem according to this invention, we now turn to Fig. 2.

Practical embodiment

In Fig. 2, 1 is a linear rheostat whose resistance equals R. By linear rheostat, I mean a resistance consisting of a straight wire or of a uniformly wound solenoid whose axis is a straight line or a circle, associated with a movable contact point by the aid of which any portion of the rheostat from O to R can be thrown into the circuit, the fraction of the resistance thus thrown in being proportional to the displacement of the movable contact point. In the particular modification chosen for illustration in Fig. 2, the axis of rheostat 1 is a straight line.

Spaced from rheostat 1, and with its contact-making edge in a fixed disposition with respect to rheostat 1, is a "special-curve resistance" 5, to be described in further detail hereinbelow. In the particular modification chosen for illustration in Fig. 2, the said contact-making edge of 5 is a straight line, parallel to the axis of 1 and directly underneath it.

Between resistances 1 and 5 and in electrical contact with each of them is a sliding member 3, made of conducting material and built sufficiently massive to have negligible resistance. In the particular modification illustrated in Fig. 2, this member has the shape of a tuning fork, but it may in practice be modified to have any suitable shape so long as it is adapted to perform the following four functions:

(1) It must be adapted to move in a straight line or circle parallel to the linear or circular axis, respectively, of rheostat 1.

(2) It must be adapted to show on a scale the amount of its displacement from position zero.

(3) It must make a point contact with rheostat 1 in any of its positions, the location of which point, however, will vary with the position of the sliding member 3.

(4) It must make a line contact with the aforementioned contact-making edge of the special-curve resist-

ance 5.

In Fig. 2, function 3 is achieved by a spur or similar contact point 32 fixed on the upper leg 31 of sliding member 3.

Function 2 is achieved by a stationary scale 2, cooperating with the forward end of one of the legs of member 3 or with a special pointer (not shown) fastened to one of said legs in a convenient position. Scale 2 represents the x-axis. In Fig. 2, the zero point of this scale is on the left and its range from 0 to 1.0 coincides in length with the length of rheostat 1 (as measured from its zero point to the point where its resistance is R). If rheostat 1 is uniformly wound, scale 2 must likewise be uniformly graduated; that is its reading must be a linear function of the displacement of member 3. Other styles of subdividing scale 2 are possible (for instance,

logarithmic), providing the design of resistances 1 and 5 is correspondingly modified.

Function 4 is achieved by the lower leg 33 of sliding member 3, which is in continuous line contact with the upper edge 52 of special-curve resistance 5.

The words "point contact" and "line contact" above are used in a relative sense, and do not take into account the third dimension of resistances 2 and 5, that is, the dimension perpendicular to the plane of the drawing. In practice, this third dimension does come into action, and the "point contact" with rheostat 1 is actually a line contact or an oblong rectangle or ellipse contact, with the longer dimension perpendicular to the plane of the drawing. Likewise, the "line contact" with special-curve resistance 5 is actually a rectangular area contact, the area being in a plane perpendicular to the plane of the drawing.

The laminated resistance

Referring now to Fig. 3, the special-curve resistance 5 has been specially invented by me and designed to serve the purposes of this invention. In its essence, it is a pile of laminated, conductors of varying heights and assembled to pave out with their butt ends a smooth plane surface of uniform width in the dimension perpendicular to the plane of the drawing, while the opposite ends define a specified mathematical curve. The individual laminae or plates 51 are actually much finer than shown in Fig. 3, the latter being merely symbolic or diagrammatic in this respect. They may consist of mutually insulated metal foil of rectangular shape, or of plastic foil coated uniformly or imprinted with a conducting film (as for instance, a metallic or graphite film). Or they may consist of fine wires suitably surfaced with a film of lacquer or with an insulating oxide film. In either event, the laminae are assembled to form a plate of uniform thickness and of a width corresponding to the length of scale 2 and are held together in this position by plastic plates or paper binding sheets 56 (see Fig. 4). The butt ends of the laminae are arranged to form a rectangular, relatively plane area 52 on one edge of the plate. The plate is then held tight in a jig, and edge 52 is machined, ground and polished to produce a smooth and true plane, rectangular surface. The thickness of the plate (i. e. the dimension perpendicular to the plane of the paper) may be varied from one design to another, but will generally be small compared to the length of edge 52, which in turn is equal to the length of the range of 0 to 1.0 on scale 2. In fact, in some designs, as explained in connection with Fig. 7 hereinbelow, the laminated plate is made thin enough to be capable of being bent into a semicircular cylinder whose base is defined by edge 52.

The opposite ends of the laminae are then cut away, machined and ground or polished to produce a curving edge 53 whose shape corresponds to a designated mathematical curve based on edge 52 as x-axis. In the preferred form wherein scale 2 is divided into uniform, linear divisions, the curved edge 53 follows a parabola. More particularly, the curve must be defined by the equation $y=Kx^2$, where K is a constant to be determined hereinbelow.

The thus formed and polished edge 53 is then made conductively integral (as by soldering) with a conducting strip 54, which is sufficiently massive to have negligible resistance. The right-hand end of this strip (assuming that the origin of x is at the left) is then extended forward or downward, to provide a contact zone 55 for connecting to electric wiring or other electrical apparatus.

The performance of this type of resistance can now be readily explained. If a flat-surfaced conducting member 33 is brought into uniform and intimate electrical contact with the butts of the laminae 51 along a portion of edge 52, and if a potential difference V is applied between element 33 and end 55, current will flow (as

shown by the arrows) across edge 52, through the individual laminae contacted by it, to conducting strip 54 and out at 55. The conductance (reciprocal of resistance) encountered by this current will be determined by the summed conductance of the laminae contacted by element 33. The more of these laminae are contacted, the less the total resistance. On the other hand, the longer each lamina, the greater is its individual resistance.

In the particular design of Fig. 3, if the range of contact covers the space between point x and point 1.0 on the scale, the integrated resistance of the laminae in action equals

$$\frac{Rx}{1-x}$$

This is the required mathematical expression for resistance B in Fig. 1.

The device as a whole

Let us now return to Fig. 2.

A battery 4 is connected across the system by contacts at point O of the rheostat 1 and point 55 of resistance 5. If key 41 in the same circuit were closed, current would flow as indicated by the arrows, from the battery through point O, along rheostat 1, through contact point 32 and leg 31 of member 3, then further across leg 33 into certain laminae of resistance 5, then out along member 54 to point 55 and back to the battery. If the position of the spur 32 (and corresponding edge of leg 33) is at x on the scale, the portion of resistance 1 thrown into the circuit is $A=R(1-x)$, while that of 5 is

$$B=\frac{Rx}{1-x}$$

35 The circuit then consists simply of a battery and two resistances A and B in series.

However, the circuit contains further a double-pole-double-throw switch 6, and a fixed resistance 7 whose value is again equal to our basic unit R. The latter is connected across one pair 61 of the outer terminals of switch 6, while the middle pair 60 of the latter are connected respectively to point 34 of member 3 and point 55 of member 5.

40 Before closing key 41, switch 6 is thrown to the right, to close the same upon said pair of terminals 61. Thus resistance 7, of fixed value R, is shunted across variable resistance B, which satisfies the basic diagram of Fig. 1.

Key 41 may now be closed, and sliding member 3 may be moved to any desired position x (within range 0 to 1.0 on the scale). And no matter what this position be, the total resistance of the circuit is R (constant); the value of A is $R(1-x)$; the value of

$$B \text{ is } \frac{Rx}{1-x}$$

55 the terminal E. M. F. of the battery is E (constant, except for temperature variations and degradation of the battery itself), and the drop of potential between points 34 and 55 is $e=xE$.

60 The principal object of this invention has thus been achieved. We have a device by which we can readily lay off a fraction xE of a specified voltage E, by merely moving a sliding member 3 to position x along a graduated scale.

65 If it is desired to vary E itself, this can be achieved by including a variable resistance in the battery circuit in series with rheostat 1, but externally to the system included between the points O and 55, or we may shunt a variable resistance across the terminals of the battery itself. These variations being readily understood by those skilled in the art, they are not shown on the drawings. The value of the basic unit R itself cannot be tampered with, once the device is built; but it may be selected at any convenient value while the design is still on the draft board.

The device up to this point may be looked upon as a voltage divider, which receives from a battery a given terminal voltage E , and delivers at its taps 34 and 55 any desired fractional value of said voltage from O to E . But accurate performance of the device can be obtained only if resistance 7 is maintained across the outer terminals of DPDT switch 6. If the delivered voltage $e=xE$ is to be put to a practical use, it will obviously be necessary to transfer it to the desired "load" (grid of a vacuum tube, meter servomechanism, etc.). This can be achieved simply by connecting the load and switch 6 to the other pair of outer terminals, 62, provided care is taken to ballast the load with variable resistances until its total resistance equals exactly R . How this is to be done in any particular case will, obviously, depend on the nature of the load and the design of its circuit. But for the purpose of illustration, Fig. 2 contains a showing of how this can be done in a particular case.

Cascaded voltage divider

The particular case of loading illustrated in Fig. 2 deals with cascaded "potentiometers" or voltage dividers. Such cascades are useful in the design of servomechanisms or analog computers. See for instance Soroka, above cited, at pages 51 to 52 (Figs. 2.9, 2.10 and 2.11) and at page 128 (Fig. 4.1). In the devices there discussed, loading effects are prevented by resorting to electron tube devices ("cathode-followers") or are ignored, which means that up to a certain degree the error introduced by loading is tolerated, while above that degree the device is simply not used.

Now according to my invention as shown in Fig. 2, terminals 62 of switch 6 are connected directly across the points O and 55 of another similar potentiometer device II. Here again points 34 and 55 are connected to the middle terminals 60 of a DPDT switch 6, whose outer terminals 61 must be spanned by a resistance of value R . But instead of using a new resistance unit for this purpose, terminals 61 may be simply connected to resistance 7 by tapping on lead wires 63.

If desired, a third similar potentiometer unit may likewise be switched in at terminals 62 of the second switch 6, and likewise a fourth and a fifth unit, provided it is remembered always to have the last switch 6 closed upon resistance 7, or upon an equivalent resistance whose value is R .

The positions of the slides 3 in the various successive units need not be identical. And if $x_1, x_2, x_3, \dots$ represents the positions of these slides in the successive units, the voltage delivered at the taps of the final unit will be $e_1=x_1E, e_2=x_1x_2E, e_3=x_1x_2x_3E$, etc., depending on how many units have been put into the cascade.

Cascades of this type can be used in servomechanisms to achieve control of a machine or of a chemical or manufacturing process, wherever it is desired to regulate a machine or process according to the mathematical product of 2 or more variable factors within the machine or process. For this purpose, each factor may be connected individually (by means of a mechanical or electrical mechanism) to a sliding member 3 of one of the potentiometer units in the cascade, whereby to move said sliding member along the x -axis in proportion to the value of the factor. The terminals of the final unit in the cascade then deliver a voltage which is proportional to the product of the individual factors. These terminals 61 of the final switch 6 in the cascade may then be connected to a suitable electrical mechanism for feeding back the proper control or regulation into the machine or process, as the particular case on hand may require.

The last mentioned electrical feed-back mechanism may be made to replace resistance 7 at the terminals 61, provided it is designed to have a total resistance equal to R and to maintain this value constant throughout its operation. But a simpler procedure is to retain resist-

ance 7 and connect its terminals to the grid of an electronic vacuum tube. The plate of the latter may then be connected, through a local battery, to any desired mechanism for performing any function whatever. For this purpose, resistance 7 is shunted by a switch 71, and the manner of its use is illustrated in Figs. 5 and 6.

Cascades of the above type may also be used in calculating machines. For instance, if we are given three fractions x_1, x_2 and x_3 , and we have a cascade of three potentiometer units, we may move manually the sliding member 3 of each of these to lay off on its respective scale one of these fractions. The product, as already stated, is then represented by the voltage drop e across resistance 7 in the final unit of the cascade. The problem now is how to read this value e .

As shown in Fig. 5, this may be achieved simply by connecting a voltmeter across the outer terminals of switch 71. Assuming that the resistance of the voltmeter is high compared to R , its reading will represent with reasonable accuracy the value of e . Then $x_1x_2x_3=e/E$. Furthermore, if E is known in advance, the voltmeter may be calibrated to read off the product $x_1x_2x_3$ directly.

In Fig. 6, the same result is achieved, with higher accuracy by the aid of a no-current, measuring circuit. For this purpose, an ordinary potentiometer including battery 81, principle resistance 82 and movable contact point or plug 83 is employed. The potentiometer may be of the sliding wire type or of the circular coil type, but in either event the device is provided with a scale to indicate the degree of movement or the fraction of terminal voltage chopped off by the plug 83. A galvanometer G , and lead wires connecting the device to switch 71, complete the circuit. But to protect the galvanometer against unexpected, excessive currents, a voltmeter V may be inserted parallel to G . A key 84 held back by a spring, or a push button device 85, then serves to keep V included in and G excluded from the circuit most of the time. In making a measurement, plug 83 is moved experimentally along resistance 82, until a point is found wherein essentially no current flows through V . The key is then pressed to exclude V and to insert G in its place, and finer adjustments in the position of contactor 83 are made, until no current flows through the galvanometer.

Systems for performing other mathematical operations such as division, squaring, cubing, taking roots, solving polynomial equations, etc., may be designed in similar manner by the aid of my novel voltage dividing device, and servo-mechanisms for carrying out analogous functions automatically may likewise be constructed. It will thus be clear that my novel potentiometer device has numerous potential applications in practice, the details of which need not be gone into any further at this point. But now, to complete the disclosure, we shall go back to the special-curve resistance 5 and discuss its theory and principles of design.

Theory of the laminated resistance

Going back to Fig. 3, let X represent the abscissa of any point on curve 53 in cm., and let y represent its ordinate. Let L represent the length of edge 52, from $x=0$ to $x=1$. Then $x=X/L$. As x varies from 0 to 1, X varies from O to L . The laminae contacted by leg 33 of slide 3 when its end is at X are those included in the region between X and L . The conductance C of this group of laminae is the sum of the conductances of the individual laminae. The resistance B of the group is the inverse of the conductance; $B=1/C$.

Let ΔA = the cross sectional area in square cm. of one lamina, ΔX = its thickness in cm. along the X -axis, b = its width in cm. perpendicular to the plane of the drawing, and y its height. Let c = the specific conductance of the conducting material of the lamina, and j its area ratio, that is, the ratio of conducting area to total area in a given section. (For instance, if our laminae are made

up of plastic foil coated with a metal film, and if the thickness of the metal film is $\frac{1}{4}$ of that of the plastic film, the cross sectional area of each lamina is $\frac{1}{8} b\Delta X$ square cm. of plastic material and $\frac{1}{32} b\Delta X$ square cm. of metal; hence $j=\frac{1}{8}\rho$. As for c , its value is $1/\rho$, wherein ρ is the specific resistance of the metal employed, expressed in ohms per cm. length for each square cm. of cross section.

The values of ρ are recorded in the literature or may be determined in the laboratory for any particular novel conducting medium. See for instance, *Handbook of Chemistry and Physics*, nineteenth edition, page 1337 to 1343. By way of illustration, a few such ρ -values are noted here.

Silver -----	$1.5-1.7 \times 10^{-6}$
Copper -----	$1.54-1.68 \times 10^{-6}$
Aluminum -----	$2.6-3.0 \times 10^{-6}$
Magnesium -----	$4.1-5.0 \times 10^{-6}$
Manganin alloy -----	$40-70 \times 10^{-6}$
Carbon (in lamp filament) -----	4000×10^{-6}

The conductance, then of 1 lamina is

$$\Delta C = \frac{c \cdot j \cdot \Delta A}{y} = \frac{jcb \Delta X}{y} \quad (1)$$

The conductance of the pack between abscissas X and L is approximately

$$C = \int_X^L \frac{jcb dX}{y} \quad (2)$$

The broader case wherein y is given different forms in terms of X to obtain corresponding varying C 's is discussed further down in this specification. For the purpose of the potentiometer problem dealt with in the instant case, it is sufficient to set $y=kX^2$. Then the definite integral is

$$C = \frac{jcb}{k} \left[\frac{-1}{X} \right]_X^L = \frac{jcb(L-X)}{kLX} \quad (3)$$

then

$$B = \frac{kLX}{jcb(L-X)} \quad (4)$$

Now, our problem above requires

$$B = \frac{Rx}{1-x}$$

wherein

$$x = \frac{X}{L}$$

Inserting and simplifying,

$$B = \frac{RX}{L-X} \quad (5)$$

Comparison of (4) and (5) shows that our problem will be satisfied if

$$\frac{kL}{jcb} = R \quad (6)$$

Replacing

$$\frac{1}{c} \text{ by } \rho$$

the formula becomes

$$R = \frac{kL\rho}{jb} \quad (7)$$

Formula 7 can be used as the basic law for designing resistor B for the purpose of this invention. For instance, let us assume that we desire to make the length of scale 2 about 10 inches, and the thickness of plate 5, 1 cm.; then we select $L=25$ cm. and $b=1$. Also, since $y=kX^2$, the highest ordinate in the plate is at $X=L$. For practical purposes, it will be desirable to keep the height of

this terminal ordinate y at about the same value as length L ; therefore we choose

$$k = \frac{1}{L}$$

then $y_m=L$. Equation 7 then becomes simplified into

$$R = \frac{\rho}{j} \quad (8)$$

If we try to make our laminae out of alternating sheets of metal foil and plastic, we shall find that the values of R obtainable are too small for practical purposes. For instance, if we make $j=\frac{1}{6}$ and $\rho=2.8 \times 10^{-6}$ (using aluminum foil), then R becomes 14 microhms. With such a low value of R , the resistances of the lead wires and contact points could not very well be neglected.

So instead of alternating plastic and metal foil, we shall use a plastic film (say, viscose or cellulose acetate film) spray-coated with a suspension of carbon black in a suitable liquid (which is then evaporated). The coating may cover the entire face of the film; yet, its extreme thinness compared to that of the film may reduce j to a very small value, say $j=\frac{1}{40}$. Assuming now $\rho=4000 \times 10^{-6}$, we obtain $R=0.160$ ohm.

25 This is a much more reasonable value of R for practical use, but we can increase it still further by reducing j and increasing ρ by various means. For instance, instead of spray-coating the cellulosic film over its entire surface, we may simply imprint upon it straight lines, 1 30 per cm., of say 0.5 mm. width. We then cut the film into strips 1 cm. wide, obtaining now a j -value 20 times as small as before. Then R becomes 3.20 ohms.

We may also dilute the concentration of the carbon black in the printing paste, thereby increasing ρ to very 35 high values. In that fashion very large values of R can be obtained.

Still higher values of R may be obtained by using 40 mutually insulated laminae made up of semi-conducting plastics. For instance, by incorporating carbon black into the melts or solutions from which plastic films (viscose, cellulose acetate, methyl methacrylate, etc.) are formed, compositions may be produced having ρ -values of the order of 10^4 to 10^5 ohms or even higher. Assuming for 45 instance a material having $\rho=5 \times 10^4$, and assuming laminae 1 cm. wide and having insulating coatings of negligible thickness, we may set $j=1$ and $b=1$; then (if $kL=1$) $R=50,000$ ohms. By altering the values of j , b and kL , further variations in the value of R may be achieved.

50 It will be clear that the value of R can be varied within very wide limits, to suit practically any particular problem on hand.

Equivalents and modifications

55 It will be noted that if L and y_m are equal, then $kL=1$ and the actual values of L and y_m become immaterial insofar as the value of R is concerned. L , however, is material in determining the fineness with which rheostat 1 and resistor 5 may be adjusted and read. The longer L , 60 the more laminae may be put into resistor B ; then the change produced by one lamina will constitute a finer fraction of the total value of B . Finally, when L is long relative to the thickness b of plate 5, the latter may be curved into a circular cylinder whose base will be formed 65 by edge 52.

It will be noted here that the laminae 51 of resistor 5, after proper arrangement and packing, are held together by two plastic sheets 56 as shown in exaggerated form in Fig. 4. These sheets may consist simply of gummed paper, or they may be plastic sheets of more or less substantial thickness, which are "welded" onto the edges of the laminae by first softening (heating) and then setting under pressure. Depending on the total thickness of the sandwiched structure thus produced, on its length in the 70 dimension of X and on the elasticity of the laminae and

binding sheets, the structure may be made flexible enough for bending into a cylindrical surface. Such bending is preferably to be done after the curved edge 53 ($y=kX^2$) has been cut out and polished, but other orders of procedure may also be applied.

If resistor 5 is thus bent into a cylindrical surface, then rheostat 1 is likewise to be replaced by a solenoid wound around a cylindrical core. Circular variable resistances of this type are quite common in radio practice. Slide 3 is then also replaced by a contactor system which revolves in a circle, and scale 2 is replaced by a circular dial.

Numerous detailed arrangements are possible in such an event. But for the sake of illustration, attention is directed to Fig. 7, wherein semicircles are employed instead of full circles. Rheostat 1 is replaced by the semi-circular solenoid 91; resistor plate 5 is bent into semicircle 95; dial 92 takes the place of scale 2. A knob 94 carries a metallic pointer 93 which contacts solenoid 91 through a suitable spur, while its extension guides an arcuate contact member 933 over semicircular member 95. Pointer 93 is made elastic or is pressed down by springs to insure good contact at 91 and 95. Rollers pressed down by springs (not shown) may further be provided to hold down semicircular strip 933 in good electric contact with member 95.

It will be remembered that the arc 95 shown in Fig. 7 corresponds to edge 52 in Fig. 2, and represents the butt ends of the lamina 951. The dimension y runs perpendicular to the plane of the drawing and in the direction away from the reader, so that knob 94 may be turned freely, without interference from the body of the special-curve resistor 95. Contact point 34 for the wiring circuit may now be any point on pointer 93, and may run through the axle of knob 96. Contact point O is now at 910, which is the zero-end of solenoid 91, while contact point 55 is, as before, at the end of y_m , which is now in the third dimension away from the reader of Fig. 7.

In Fig. 7, the dial is preferably laid off not in degrees of arc but in decimal parts of the total active arc involved in the resistor B.

It will be understood from all the foregoing that my invention is susceptible of wide variation as to form, without departing from the spirit thereof. For instance, instead of placing the unit 5 directly under rheostat 1 in Fig. 2, to be joined electrically by a sliding member shaped like a tuning fork, the two resistances may be placed side-by-side as in Fig. 8 to be operated by a somewhat boat-shaped sliding member 3a. Or they may be placed at an angle with respect to each other, replacing slide 3 by a suitable mechanism achieving the two contacts, in their respective angular directions, simultaneously.

Rollers held down by springs (not shown) may be provided to hold spur 32 and leg 33 of member 3 in firm contact with their respective resistors.

Instead of a scale 2, graduated in decimals to indicate the displacement of slide 3 as a fraction x of the maximum possible displacement, it may be calibrated in any other manner to read for instance millivolts, degrees of arc, pressure in pounds per square inch, or any other quantity of interest in any particular practical problem.

Instead of battery 4 in Fig. 2, a standard cell (of known voltage) may be employed, together with suitably placed, adjustable resistances in series, so as to convert the unit into a direct-reading potentiometer.

In a cascaded system the set of successive switches 6 may be replaced by a single bank of switches so designed that it is impossible to throw any particular member of the bank from terminals 61 to terminals 62, without automatically closing the switch in the next unit of the cascade upon terminals 61, so as to insure sealing the entire cascade by fixed resistance R.

Numerous other changes in detail will be readily apparent to those skilled in the art. A particularly inter-

esting modification of this invention is discussed in the following paragraphs.

Special modification

Instead of using for rheostat 1 the traditional straight wire or a uniformly wound solenoid, we may use for this purpose another laminated resistor built on the same general principles as resistor 5, but having as y a straight line, sloping from 0 to y_m . Unlike resistor 5, however, the resistance used here is that of a single element y instead of the integrated sum of the y 's in a specified region. The details of such a rheostat are shown in Fig. 9, while its use in conjunction with resistor 5 is illustrated in Figs. 10 to 12.

In Fig. 9, the resistor-plate 10 is made up of mutually insulated conducting laminae 101, whose butts are lined up and polished to form the straight line 102. This constitutes the x -axis, which varies from 0 to 1, or the X-axis which varies from O to L. (It is clear that $x=X/L$.) The heights of the laminae are defined by the equation $y=m(L-X)$ or $y=mL(l-x)$; their ends opposite to the aligned butts therefore outline a straight line 103 which slopes from y_m to 0. (As in the case of resistor 5, "line" here is used in a relative sense. Actually, the laminae have width b in the dimension perpendicular to the drawing, and edges 102 and 103 are plane surfaces.)

In "welded" contact with this sloping edge 103 (by which I mean a fixed and intimate contact) throughout its length is a low-resistance (metallic) conducting strip 104, whose lower end 105 corresponds to point O in Fig. 2 and is connected to battery 4. Along the edge 102 moves contact-spur 32 at the end of leg 31 of sliding member 3. The current flow follows the arrows shown in Fig. 9. Entering from the battery through point 105, the current flows up the conducting strip 104 to the ordinate (or small group of ordinates) y which is in contact with spur 32, and then out along leg 31. Theoretically, spur 32 should be a knife-edge, so as to contact but one of the y 's. Actually, however, it may be a small area, having a finite width along the x -axis, so that contact is made with a bundle of neighboring laminae. However, the height y_m of the tallest lamina as well as the thickness and j -value of each must be designed with a particular width of spur 32 in view, and once so designed, the spur must not be replaced by one of different contact area. The calculations involved in the design of this resistor 10 are as follows:

For each lamina of height y , the conductance is

$$\Delta C = \frac{jcbt}{y}$$

wherein j , c , b and y have the same meaning as above, while t represents the thickness of each lamina in the direction of the X-axis. The resistance, then, is

$$r = \frac{\rho y}{jb} \quad (9)$$

If a single lamina is contacted by spur 32, this is the value of A required according to Fig. 1. If more than 1 lamina is involved in the contact, their total conductance is the product of their average multiplied by their number. Their net resistance is therefore approximately equal in value to the resistance of the median y divided by the number of y 's contacted. This drop in resistance must be compensated for in the selection of the slope-coefficient m for the expression $y=m(L-X)$.

For instance, let ΔX = width of spur 32 along the X-axis, and let $\Delta X = nt$; then

$$A = \frac{\rho y}{njb t} = \frac{\rho y}{j b \Delta X} \quad (10)$$

At the higher edge of the plate, $y=y_m$, and at that point it is required that $A=R$; hence,

$$\frac{\rho y}{jb\Delta X} = R \quad (11)$$

Let $y=m(L-X)$; at y_m , $X=0$; therefore, $y_m=mL$. Inserting in (11),

$$\frac{mL\rho}{jb\Delta X} = R$$

or

$$m = \frac{Rjb\Delta X}{\rho L} \quad (12)$$

If R , j , b , ΔX and ρ have been selected, m can be readily computed. Then finally,

$$A = R \frac{L-X}{L} = R(1-x) \quad (13)$$

which agrees with our requirement under the theory of Fig. 1.

According to Figs. 10 and 11, the two resistor plates 10 and 5 are superimposed upon each other with their planes preferably parallel to each other, and with their sliding-contact edges 52 and 102 likewise parallel. Slider 3 is then modified mechanically to meet the new geometrical disposition.

When this particular construction is selected, then L is necessarily the same for both laminated plates.

Principles of design

In practical design, it is desirable to have the dimensions of the plates 5 and 10 of the same order of magnitude. Letting Y_B represent the highest ordinate in plate 5, and Y_A the highest ordinate in plate 10, it is desirable to have both Y_B and Y_A roughly equal to L . By the formulas above derived for resistor B, $y=kX^2$, wherein

$$k = \frac{Rjcb}{L} = \frac{Rjb}{\rho L} \quad (14)$$

and the highest ordinate is at $X=L$; therefore $Y_B=kL^2$. For resistor A, $y=m(L-X)$, wherein

$$m = \frac{Rjb\Delta X}{\rho L} \quad (15)$$

and the highest ordinate is at $X=0$; therefore, $Y_A=mL$. If $Y_A=Y_B$, then $m=kL$. If we want Y_A and Y_B both to equal L , we must choose

$$k = \frac{1}{L} \text{ and } m = 1$$

This aim, however, cannot be realized under practical conditions of design unless we choose different values for the expression

$$\frac{jb}{P}$$

in the two coils. So, let j_A , b_A and ρ_A represent these values for resistor A, and j_B , b_B and ρ_B the corresponding values for resistor B. Then we obtain from (14) and (15)

$$Rj_Bb_B = k\rho_B L \quad (16)$$

and

$$Rj_Ab_A\Delta X = m\rho_A L = k\rho_A L^2 \quad (17)$$

Dividing (17) by (16),

$$\frac{j_A b_A \Delta X}{j_B b_B} = \frac{\rho_A}{\rho_B} \quad (18)$$

(18) then may be considered as the basic formula for design, when resistors A and B are constructed as in Figs. 9 and 10. However, we may still set $b_A=b_B$ (which implies equal thickness in plates 10 and 5); then

$$\frac{j_B \rho_A}{j_A \rho_B} = \frac{\Delta X}{L} \quad (19)$$

Assuming that we now choose 25 cm. as a convenient value for L , and 0.25 to 0.5 mm. as a suitable value for ΔX (which is the width of the contact area of spur 32), then

$$\frac{\Delta X}{L}$$

is about

$$\frac{1}{500} \text{ to } \frac{1}{1000}$$

This, then, is the practical value of the left-hand member of (19).

We may still choose $j_A=j_B$ (which implies making the ruled conducting lines on the plastic laminae of the same width and thickness for both resistor A and resistor B). Then (19) compels us to choose ρ_A and ρ_B so as to have a ratio between 0.002 and 0.001. This condition can be satisfied by choosing a graphite ink for resistor B ($\rho=800$ microhms) and a silver printing ink for A ($\rho=1.6$ microhms), or by choosing filament carbon for resistor B ($\rho=4000$ microhms) and cadmium for resistor A ($\rho=8$ microhms). Other convenient combinations can be readily selected from tables of resistivity in the literature. (See for instance, *Handbook of Chemistry and Physics*, 19th edition, pages 1337 to 1343.)

Finer adjustments of the ratio (19) may be made by varying the j 's as well as the ρ 's. For instance, we may print the plastic foil with conducting inks to produce a thin line for the one resistor, while spraying the entire surface of the foil with its respective conducting paint for the other conductor. Or again, we may print the foils in both cases, except make the imprinted lines of different widths or thicknesses in the two cases. For instance, by making the silver line for resistor A about $4/3$ times as wide as the graphite line for resistor B (keeping the b 's equal, as above), we obtain from (19) a ratio of 0.0015; then, if $L=24$ cm., ΔX can be made equal to 0.36 mm.

Simplified design procedure

The above discussion solves the problem insofar as selecting the requisite materials and mode of printing are concerned. The actual design, however, may still be difficult, because it would require precise knowledge of the resistivity values of the inks selected and the j -values of the imprinted conducting lines. To avoid this ambiguity, I propose the following procedure for building and shaping resistors A and B.

Having chosen the requisite plastic film (cellulosic film, polyvinyl, methacrylate, etc.), having settled upon the desired values of L , b and ΔX , having settled upon the printing-ink pair to be chosen (say, graphite and silver), and having estimated approximately the desired width and thickness of the imprinted line, proceed now as follows:

(1) Print the film in two sets with their respective inks, the printed lines being spaced off at intervals corresponding to the chosen b -value.

(2) Cut the imprinted films transversely of the imprinted lines, to give sheets of width slightly greater than the selected L . (The excess is simply to provide a margin for finer trimming and polishing.)

(3) Chop each sheet (by the aid of a suitable slicer, chopping machine or power shears) in a direction parallel to the imprinted lines, to give strips of width b .

(4) Stack the strips into piles of convenient height (say, 1 or 2 inches) and press them together (with or without application of heat to soften the plastic) to give compact sticks, which will now have the dimensions of

L cm. long, b cm. thick, and perhaps 2 to 4 (or more) cm. wide.

(5) Place several of these sticks together tightly along their width, until their total width equals about L , thus obtaining a square, roughly L cm. on each side and b cm. thick.

(6) Place a binding sheet of thermoplastic material (say, methyl methacrylate) on each face of each square, and apply heat and pressure until the system has become welded, so to speak, into a continuous, single plate.

(7) Trim or polish the edges of each square to perfect it to the dimension L on each side.

(8) Now, taking one of the plates intended for resistor B, apply a pair of negligible-resistance electrodes (i. e. contacting strips of metal, similar to leg 33 above) to the edges of the square which contain the butt ends of the laminae, and using a dry cell, a millivoltmeter, standard adjustable resistances or potentiometers (or whatever other apparatus may be needed), measure the resistance of the entire square in the direction of the ruled conducting lines. Let T represent this total resistance. Then

$$\frac{j_B b}{\rho_B} = \frac{1}{T} \quad (20)$$

{Proof:

Going back to Equation 1 above, replace y by L and integrate between the limits 0 and L ; also, replace c by $1/\rho$. Then

$$C = \int_0^L \frac{j_B b dX}{L} = \frac{j_B}{\rho} X \Big|_0^L = \frac{j_B}{\rho} L$$

$T = 1/C.$

(9) Taking one of the laminated plates intended for resistor A, apply to it, on one of the butt-end edges, one of the contacting spurs 32 which have been designed for use with the resistors A of this set in the subsequent assembly of the potentiometer units. (This implies a pre-arranged design of slide-member 3 or at least of its spur 32, and a faithful adherence to this design in the subsequent assembly.) Attach a negligible-resistance electrode to the opposite edge of the plate, and using dry cells, voltmeters, etc., measure the resistance of the plate lengthwise of the ruled lines. (Note that the resistance now is not that of the entire plate, but only of that group of laminae which are contacted by spur 32.) Let P be the value of the resistance thus measured. Then

$$\frac{j_A b \Delta X}{\rho_A L} = \frac{1}{P} \quad (21)$$

(Proof: In Equation 1 above, replace y by L and c by $1/\rho$. Observe that $P = 1/\Delta C$.)

Dividing (21) by (20),

$$\frac{j_B \rho_A}{j_A \rho_B} = \frac{T \cdot \Delta X}{P \cdot L} \quad (22)$$

If the j and ρ -values were perfectly selected to satisfy Equation 19, then T and P would be found equal to each other. In actual practice, we shall more often not find them equal. Then instead of pursuing the difficult task of adjusting ρ and j , we shall resort to the easier device of adjusting k and m .

(10) Compare Equations 15 and 21; then

$$m = \frac{R}{P}$$

Recalling that $y = m(L - X)$, which gives $Y_A = mL$, lay off now, on the square intended for resistor A, an ordinate

$$Y_A = \frac{RL}{P} \text{ cm.}$$

on the edge intended for $X=0$; draw a straight line from the ordinate Y_A to the corner point ($X=L$, $y=0$). Cut and polish the plate along said straight line, and apply thereto conducting strip 104.

(11) Compare Equations 14 and 20; then

$$k = \frac{R}{TL}$$

Recalling that for resistor B, $y = kX^2$, simply plot on the B-plate the parabola

$$y = \frac{RX^2}{TL} \quad (23)$$

(As a check, observe that when $X=L$,

$$y = y_B = \frac{RL}{T}$$

10 Then cut out and polish the plate along the plotted curve, and apply thereto conducting strip 54.

It will be clear, of course, that such determination of T , P , k and m will be required only once for each novel design; afterwards, the dimensions may be duplicated unto replicas of this design by standardized jigs or any suitable means.

Furthermore, if especially wanted, both plate 10 and plate 5 may be bent into a semicircular cylinder, scale 2 then being replaced by a dial. But in such event the value of the two L 's will be different for the two resistors, being in fact proportional to the radii of the respective semicircles. The above principles of design must then be modified to take into account the said difference in the values of L_A and L_B .

25 Control of accuracy

The mathematical accuracy of the device of my invention will depend first of all on the number of laminae in the plates 5 and 10. For instance, if $L=25$ cm., and if the laminae are made up of plastic film whose thickness is 0.01 cm., there will be 2500 such laminae in the range 0 to L . Inclusion or exclusion of one such lamina under slide 3, determines the smallest change that may be made in the values of resistances A and B laid off. The degree of precision is then 1 in 2500 or 0.04%. To make use of this high degree of precision, it is necessary to provide means for adjusting the position of slide 3 to within 0.01 cm. A screw-feed device would readily achieve this result; such a device is suggested in Figures 10 and 11, wherein the stem 30 of slide 3 is threaded and passes inside a bored block 36 which is held in the fork of support 37. If the bore of this block be threaded, rotation thereof within the confined space of the fork will advance or recede slide 3 along the x -axis.

45 However, instead of forming a complete circular body with a threaded bore, block 36 is preferably made up of two circular segments. This is shown in Fig. 12. Segment 360 covers some 300° of arc or more, and has a smooth bore, large enough to rotate freely over stem 30 of slider 3, without engaging its thread. The remainder of the circuit is completed by the wedge-like segment 361, which is threaded on the inner end to mesh with the thread of stem 30. Normally segment 361 is held out of mesh with the threaded stem by spring 362, which is fastened to segment 360. This enables free sliding of stem 30 through the bore of block 36. But when a screw-feed motion is desired, wedge 361 is pressed down with the thumb until it engages the thread of stem 30. Rotation of the block, effected by the thumb and fingers, then imparts a micrometer-type motion to slide 3. Needless to say, segment 360 may be engraved with a scale to indicate the amount of rotation or the amount of forward motion imparted to slide 3.

60 Other variations in detail, will be readily apparent to those skilled in the art. For instance, scale 2 may be placed between the two laminated plates, or in any other convenient position. Rollers, held down by springs, may be provided to press leg 33 and spur 32 tightly against the butts of their respectively contacted laminae. Proper supports or housing may be provided for the various elements of the device, and the latter may be insulated from such supports where necessary or, on the contrary, may be grounded through them.

Instead of laying out the lamina in plates 5 and 10 75 strictly in straight line formation, they may be bent into

arcs or sinuous curves, provided their actual lengths, not their height above the x -axis, is taken into account in laying off the curves $y=kX$ and $y=m(L-X)$. This principle is illustrated in Fig. 13, wherein the dotted outline shows the modified shape of plate 5 before cutting out the curve y , while the solid outline shows the finished resistor B. The ends 512 of laminae 51 are bent backward slightly to expose the printed face of each lamina for slightly better contact with leg 33 of slide 3. The same principle may be applied, if desired, to the ends 513 of the lamina, or to the laminae of resistor A.

Furthermore, the imprinted conducting lines may be flared out in the process of printing to form a T at that end of each lamina which is intended to make contact with slide 3, so as to provide a wider line of contact with leg 33 or spur 31. However, the height of the widened butt thus formed should be discounted (because of its lower resistance value) in computing the curve $y=kX$ or $y=m(L-X)$.

Instead of finishing off edge 52 of plate 5 in the form of a plane surface, of length L and width b , this edge may be made trough shaped or slightly grooved, with the butt ends of the imprinted conducting lines at the bottom of the trough or groove, so as to protect these ends against abrasion in handling. The contacting member 33 will then naturally be given a convex or V-shaped edge on the lower side, so as to insure proper contact with said conducting butts. Similar grooving may also be applied to any of the other edges 53, 102 and 103 above discussed, with corresponding convexing compensation in the contacts 32, 54 and 104.

In making the measurements as above of a sample plate from each set to determine the values of

$$j_B b$$

$$\rho_B$$

and

$$\frac{j_A b \Delta X}{\rho_A L}$$

other shapes than a square may be measured (for instance, a right isosceles triangle obtained by cutting one such square along its diagonal), provided corresponding revision is made in the mathematical relations involved.

Surface printed modification

Still another modification according to this invention uses for variable resistances A and B plane-printed resistors. These resistances differ from those already described in that they are not laminated. Instead, a series of parallel lines are printed, in close proximity, with a conducting ink on a non-conducting surface. Such a resistor, suitable for variable resistance B above described, is shown in Figs. 14 and 15, the latter being a section of the former along line 15—15.

A plate 12, which corresponds to plate 5 in Fig. 3, is imprinted with a series of parallel, vertical lines 121 by means of a conducting ink. The plate 12 may be of ceramic material, and the conducting ink may be a silver ink, in which case the plate is first imprinted and then fired, to produce an intimately bonded imprint. Or the conducting lines may be imprinted on a sheet of plastic material, and the latter may then be bonded, for instance by adhesive, to a plate 12 may of any convenient material such as cardboard, wood, plastic or metal. In the latter event, the imprinted sheet may be initially of rectangular shape, and may be subsequently cut out into the shape indicated in Fig. 14 as required for its intended use.

The lines and their spacing in Fig. 14 are indicated diagrammatically. Actually, the lines are much finer, and their spacing much closer than shown in this figure. In the printing of plastic sheets with copper foil by the etching method, it is not uncommon to make the lines 0.00135 inch thick and 0.005 inch wide. (Modern Plastics, August 1951, pages 99 to 111.) In printing paper

with carbon inks, very fine printing may likewise be achieved.

Let b represent the period of the pattern, that is, the distance from the leading edge of one line to the leading edge of the next line. Then each element of height y and width b on the imprinted sheet is equivalent to one lamina in the laminated modifications. The resistance of such element is

$$\frac{\rho y}{\Delta A}$$

where ΔA represents the cross section of one of the imprinted lines. For instance, if lines of copper foil of the above width and thickness are imprinted,

$$A = 0.005 \times 0.00135$$

i. e. 6.75×10^{-6} sq. in. or about 43.5×10^{-6} sq. cm. The conductor being copper, ρ is about 1.7×10^{-6} . The resistance of each element, then, is about $0.039y$. If y is given a height of 25 cm. at its highest point, the resistance of the highest line is about 1 ohm. This design then is suitable for making resistor A.

For resistor B, a carbon or graphite ink is to be chosen, and its ρ -value will be of the order of 3000 to 4000 microhms. Otherwise, the calculations are as above.

25 An element of width b has a resistance of

$$\frac{\rho y}{\Delta A}$$

or a conductance of

$$\frac{\Delta A}{\rho y}$$

If an element of width ΔX is considered, its conductance is

$$35 \quad \Delta C = \frac{\Delta X \cdot \Delta A}{b \cdot \rho y} \quad (24)$$

Comparing this with Formula 1, except restating the latter as

$$40 \quad \Delta C = \frac{j b \Delta X}{\rho y} \quad (1a)$$

we observe that we need merely to replace the expression jb by

$$\frac{\Delta A}{b}$$

45 to convert (1a) into (24). The same replacement if carried consistently throughout the remaining Formulas 2 to 23 will yield corresponding formulas for design in the instant case, that is, using surface-imprinted plates as resistors.

50 With a printed plate of the above type, contact may be made with a portion of the imprinted line instead of with its butt end. For this purpose, each y on plate 12 is laid off with small extensions z_1 and z_2 on the ends. Slide 133 along edge 122 (corresponding to leg 33 of slide 3 in Fig. 3), then is given a cross-sectional shape as shown in Fig. 15, whereby it makes contact on the surface of plate 12 along the extensions z_1 . Along edge 123, likewise, a fixed contact member 124 is provided which bends over the surface of the plate and covers up the extensions z_2 of the ordinates. Obviously, the mathematical relation $y=kX^2$ above postulated, contemplates as y the length of each ordinate between said extensions (exclusive of the latter).

65 The imprinted y -lines need not be perpendicular to the x -axis. Instead, they may be inclined, as shown in Fig. 16, provided it is remembered that it is the length of each y (exclusive of its extensions z), and not its vertical projection, that should correspond to the basic formulas above derived. Of course, where the conducting lines are imprinted on a thin, plastic sheet or paper, it is not necessary to print the lines in inclined form. Instead, the lines may be printed perpendicular to the edge of the sheet, but the latter may then be cut out properly to give the shapes indicated in Fig. 16.

Plate 14 in Fig. 16 corresponds to laminated plate 10 in Fig. 9, except that here we use a surface imprinted plate in lieu of a laminated composite plate. The extensions z_3 , z_4 here, and the fixed contact member 144 serve here the same purpose as the respective elements z_1 , z_2 and 124 in Fig. 14. Sliding contact here is made with spur 132 of slide 13, which is shown in greater detail in Fig. 18. Contact points 125 and 145 play here the same role as points 55 and 105 in Figs. 3 and 9.

The advantage of using inclined lines as in Fig. 16 is that it condenses the outline of the combination into a rectangular, almost square, space. This fact, together with the flat, and relatively thin, aspect of the resistor plates makes the modification of Fig. 16 particularly advantageous for cascading several units together; for then the several units may be stacked on top of each other, producing a compact cascaded assembly.

I claim as my invention:

1. In a device of the character described, the combination of a variable resistance A with a compound resistance consisting of a variable resistance B in parallel with a fixed resistance R, said resistance A being connected in series with said compound resistance, and means associated with said combination for varying resistances A and B in unison whereby to maintain between them the mathematical relation $AB=R^2x$, x being an arbitrary number of value between zero and 1, and whereby furthermore the total resistance of the combination is maintained at the fixed value R, regardless of the value of x selected.

2. In a device of the character described, a circuit comprising a source of E. M. F. in series with a system of resistances, said system including a variable resistance A, a variable resistance B and a fixed resistance R, said resistance B and fixed resistance R being connected in parallel to form the subcombination $\overline{BR}$, and said variable resistance A being connected in series with said subcombination $\overline{BR}$, and means for varying simultaneously the values of resistances A and B, said means being designed to move in a path of total length L and being adapted to halt at any position xL along said path, x being a number of value between zero and 1, said variable resistance A being designed to assume the value $R(1-x)$ when said moving means is at position xL , and said variable resistance B being designed to assume the value

$$\frac{Rx}{1-x}$$

at the same moment, with the result that the total resistance of the series-parallel system A— $\overline{BR}$ is maintained steady at the value R regardless of the value of x , and that the potential difference across the terminals of said subcombination $\overline{BR}$ is equal to xE , E being the potential difference between the terminals of said system A— $\overline{BR}$.

3. A device of the potentiometer type comprising in combination a variable resistance A in series with a branched resistance $\overline{BR}$, the latter consisting of a variable resistance B in parallel with a fixed resistance R; means to impress a voltage E upon the terminals of said series system A— $\overline{BR}$; a sliding contact member adapted to con-

tact simultaneously resistances A and B whereby to determine their respective effective resistance values by the position of said contact member, and conducting elements connected to the terminals of said resistance R whereby the potential difference e across said resistance R may be measured or utilized.

4. A combination as in claim 3, said resistances A and B being so designed that the total resistance of the combination A— $\overline{BR}$ is maintained at a steady value equal to R regardless of the position of said sliding contact member.

5. A combination as in claim 3 comprising further a switch associated with said fixed resistance R, whereby the latter may be excluded from the system and replaced by a circuit having a net resistance equal to R.

6. A combination as in claim 3 comprising further another potentiometer type device of the same structure, and a switch associated therewith and with resistance R of the first potentiometer circuit, whereby said resistance R may be excluded from the first potentiometer circuit and replaced by said second potentiometer circuit.

7. A combination as in claim 6 including further means whereby said fixed resistance R is shifted from the circuit of the first potentiometer into the circuit of the second, while the terminals of the system A— $\overline{BR}$ in said second potentiometer circuit are switched into the first circuit in the position formerly occupied by said fixed resistance R.

8. A cascaded system of potentiometer circuits comprising a plurality of electrically similar potentiometer units, each unit being composed of a variable resistance A in series with a variable resistance B, each next unit in the system having the terminals of its series combination A—B shunted across the terminals of resistance B in the immediately preceding unit; a fixed resistance R shunted across the terminals of the last resistance B of the system, and means associated with the variable resistances A and B of each unit whereby to maintain the effective resistance of the A—B series in each unit at a fixed value R as long as each intermediate B resistance has shunted across its terminals the respectively following unit above set forth and as long as the B resistance of the last unit has shunted across its terminals said fixed resistance R or an electrical system of equal resistance.

9. A cascaded system as in claim 8, said last unit having switching means associated with said fixed resistance R whereby to replace the latter by an electrical circuit of optional composition.

UNITED STATES PATENT OFFICE
Certificate of Correction

Patent No. 2,831,158

April 15, 1958

David Katz

It is hereby certified that error appears in the printed specification of the above numbered patent requiring correction and that the said Letters Patent should read as corrected below.

Column 3, line 65, for

$\frac{R}{R_1}$ read $\frac{R_1}{R}$

column 7, line 10, after "meter" insert a comma; column 13, lines 13 and 48, for "m-", in each occurrence, read —m=—; line 55, for "P" read —p—; column 17, line 64, for "may" read —made—; same line, for "conventent" read —convenient—.

Signed and sealed this 5th day of August 1958.
